UNITED STATES PATENT OFFICE

RUDOLPH ANTHONY SKRIBA, OF CHICAGO, ILLINOIS, ASSIGNOR TO WESTERN ELECTRIC COMPANY, INCORPORATED, OF NEW YORK, N. Y., A CORPORATION OF NEW YORK

ABRADING APPARATUS

Application filed April 27, 1927. Serial No. 186,839.

This invention relates to abrading apparatus, and more particularly to apparatus for wet grinding.

The object of this invention is to provide a simple and efficient wet grinding apparatus embodying means having a wide range of adjustment for applying liquid to the abrading element.

The features of this invention are particularly well adapted for use with grinding apparatus wherein it is necessary to apply a liquid spray to the grinding elements in order to eliminate dust and other foreign particles produced during grinding operations.

In accordance with one embodiment of this invention as applied to a grinding apparatus employing a plurality of rotary grinding wheels, nozzles are provided whereby water is ejected by air pressure in the form of spray against the face of each wheel, the nozzles each being mounted on a vertical pivot for independent arcuate movement across the face of the associated wheel and also for spraying either side face thereof. The vertical pivot is also adjustable in a horizontal direction toward the grinding wheel as it becomes worn and the nozzle is arranged to limit the adjusting movement of an air and water needle valve thereof. Readily removable receptacles mounted in depressed pockets formed in a hollow supporting pedestal below each wheel collects the spent spray and prevents the return thereof to a water supply receptacle mounted on the inside of a vertical door hinged to the lower part of the pedestal.

Other objects and advantages of this invention will become clearly apparent in the following detailed description, reference being had to the accompanying drawings, wherein

Fig. 1 is an elevational view of a wet grinding apparatus embodying the features of this invention;

Fig. 2 is a side view thereof;

Fig. 3 is an enlarged vertical sectional view of an air operated water spray nozzle;

Fig. 4 is a section on the line 4-4 of Fig.

3 looking in the direction indicated by the arrows;

Fig. 5 is a fragmentary enlarged sectional view of a snap switch embodying means for simultaneously controlling the air to the nozzle and for connecting an electrical circuit to a motor for driving the grinding wheels;

Fig. 6 is a detail section on the line 6-6 of Fig. 3 looking in the direction indicated by the arrows, and

Fig. 7 is a diagram of the electrical circuit employed.

Referring now to the drawings in detail wherein like reference numerals refer to similar parts, a hollow pedestal 10 carries upon its upper surface an electric motor 11, opposite ends of the shaft thereof having fixed thereto grinding wheels 12.

Mounted in the hollow pedestal 10 near its base is a receptacle 13 for holding a supply of water, which in the operation of the apparatus is drawn therefrom and sprayed either onto the peripheral or the side working faces of the grinding wheels 12 by means to be described hereinafter. To facilitate the filling of the receptacle 13 with water it is fixed to the rear wall of a closure or door 14 hinged at its lower horizontal end upon the front wall of the pedestal 10. A pivotal handle 17 is provided upon the door 14 to move the receptacle 13 to its filling position, indicated by broken lines (Fig. 2), and to lock the door in its closed position a latch 18 is fixed to the inner end of a pin 19 to the outer end of which the handle 17 is attached. Within the pedestal 10 above the receptacle 13 is a snap switch 20 for controlling an electrical circuit (Fig. 7) connected to the motor 11, a key 21 for operating the switch being arranged in a convenient position at the front of the apparatus and projecting through a removable panel 22. The panel 22 at its lower end is provided with a latchable hinged section 23, which provides access to a fuse block (not shown) mounted within the pedestal 10. Referring particularly to Fig. 5 the key 21 is fixed to a stem 24 of the switch 20, the stem having formed integral therewith a cam portion 25. Arranged to engage the cam portion 25 is a spring pressed reciprocal stem 28 of

100

an air valve 29 which is connected to a suitable source of compressed air (not shown) through a line 30, an air outlet line being indicated at 31. The arrangement between the switch 20 and the valve 29 is such that simultaneously with the closing of the switch the valve 29 is opened and vice versa. The compressed air valve 29 being of a well known type it is believed no detail description there-
of is necessary, since it does not form a feature of this invention. Removably mounted in depressed pockets formed in the upper end of the pedestal 10 and below each of the wheels 12 is a pan 32 for collecting the water condensed from the atomized spray directed against the wheel whereby the used or spent water is kept separated from the fresh supply contained in the receptacle 13.

Upright brackets 35 are fixed to the upper surface of the pedestal 10, one directly behind each of the wheels 12, and support the water spraying means hereinbefore referred to and which will be described presently. As each of the grinding apparatus disposed at either end of the shaft of the motor 11, as viewed in Fig. 1, is identical, a description of the bracket 35 at the right end of the shaft and the spraying means supported thereby will be given. The bracket 35 it will be noted, referring to Fig. 2, extends upwardly from its base portion which is secured to the top surface of the pedestal 10 and then curves forward around the wheel 12 and terminates in a bifurcated portion 36 centered directly above the grinding wheel 12. Formed integral with the bracket 35 is a hood 37 extending across the front of the wheel 12 and rearward along each side thereof for a sufficient distance to collect any spray of water thrown off by the wheel. Hinged vertically, as shown at 38, to each of the brackets 35 upon their outer sides, as viewed in Fig. 1 and at the rear of the wheels 12 (Fig. 2), is a cover or guard 41 provided with a recessed portion 42 for covering the end of the motor shaft and the means (not shown) for securing the wheel 12 thereto. The guard 41 is maintained in its closed position as shown in Figs. 1 and 2 by means of a thumb screw 43 (Fig. 2) which is operatively associated with the guard and the bracket 35. When changing the grinding wheel the thumb screw 43 is released whereupon the guard 41 may be swung outwardly to remove the wheel after swinging upwardly an adjustable front guard 44. The guard 44 is pivoted at 45 upon the bracket 35 and may be adjusted upwardly or downwardly as desired, the position thereof being maintained by a wing nut 46 (Fig. 1).
60 Mounted between the arms of the bifurcated portion 36 of the bracket 35 is an L-shaped member 49 (Figs. 3 and 4) comprising a holder for a water spraying nozzle or air operated atomizer indicated generally by 85 the numeral 50. A horizontal arm 51 (Figs.

3 and 4) of the holder 49 is rectangular in cross-section and fits closely between the inner opposed surfaces of the arms of the bifurcated portion 36 of the bracket 35 and is rigidly retained in a predetermined horizontal position upon the bracket by means of a thumb screw 52 threaded into a cross plate 53 secured to the arms of the bifurcated portion 36, the inner end of the screw bearing against the upper surface of the support 49. Upon the grinding wheel 12 wearing down to such a degree that the nozzle 50 is not properly directing the atomized spray onto the periphery of the wheel, the thumb screw 52 is released from its clamping engagement with the arm 51 of the holder 49, whereupon the latter may be moved toward the right (Fig. 3) upon the bracket 35 until the nozzle will properly direct the spray, and thereafter reclamped. Water and compressed air lines 54 and 55, respectively, connected to the arm 51 are arranged and composed of such material that they readily flex during the adjustment of the nozzle 50 as just described without any appreciable harm thereto. Pivoted upon a circular shaped tapered vertical arm 56 of the support 49 is a nozzle casing 57 provided with an aperture 58 shaped to fit the arm 56. The nozzle casing 57 is secured upon the arm 56 by a nut 59 threaded onto a stem 59 of the arm 56, a spring washer 60 surrounding the stem between the nut and the casing 57 adjacent the circular tapered surface of the arm 56 to thereby provide such a fit therebetween that leakage of air and water which, as will be presently described, passes through the holder 49 and into the nozzle casing, will not occur and also to provide means for maintaining the casing in its adjusted position upon the holder, the arm 56 serving as a vertical pivot for the casing.

An air and water needle valve carried by the vertically pivoted casing 57 and comprising therewith the water spraying nozzle 50 or air operated atomizer hereinbefore referred to will now be described.

The casing 57 of the nozzle 50 upon its left side (Figs. 2 and 3) is angularly disposed whereby the atomized spray may either be directed against the periphery of the wheel when in the position shown or against either side face thereof when turned upon its vertical pivot toward the left or right as viewed in Fig. 1. The angularly disposed portion of the casing 57 is provided with a shouldered aperture 63 which at its upper end is enlarged to receive a valve gland 64 threaded thereinto, the gland being provided with a threaded aperture 65 for receiving a valve needle 66 in the form of a shouldered tube provided with a main longitudinally extending aperture 67 which is greatly reduced in size at its lower end, as indicated at 68, the diameter of the needle 111

surrounding the aperture 68 also being reduced in diameter. The upper extremity of the needle 66 is provided with an enlarged circular head portion 70, the corresponding end of the aperture 67 being closed by a plug 71 threaded thereinto. Fixed to the head 70 of the needle 66 by a set screw 72 is a circular knob 73 for adjusting the needle whereby the nozzle 50 may be set to emit a desired water spray upon the periphery of the wheel 12 as will be fully described presently. A circular shoulder recess 74 is formed in the underside of the knob 73 for receiving the head 70 of the needle 66, while an enlarged portion 77 of the recess receives a hexagon shaped head 78 of the valve gland 64. A nut 79 threaded onto the valve gland 64 is for the purpose of locking the latter member in position. The circular wall of the gland 64 at its lower end is slotted at right angles to the longitudinal axis of the aperture 65 to provide four passageways 80 spaced on 90° centers (Fig. 6) for passage of compressed air from an annular chamber 81 formed in the casing 57 along the aperture 63 thereof and into a passage 82 formed in the needle 66 at right angles to its longitudinal aperture 67. Slidably fitted in the aperture 63 and around the needle 66 and positioned below the slotted end of the gland 64 is a brass collar 83, the collar abutting a packing collar 84 composed of suitable material, such as felt, fitted within the aperture 63 and around the needle 66, the lower surface of the latter collar abutting a shoulder formed in the aperture 63. By threading the gland 64 downwardly the collar 84 may be compressed sufficiently to prevent the escape of air from the annular chamber 81 into an annular chamber 85 formed in the casing 57 between the walls of the aperture 63 thereof and the peripheral surface of a reduced diameter of the lower end of the needle 66, this latter chamber being a water chamber. Threaded onto the lower extremity of the casing 57 is a tip 86 provided with a spray aperture 88. Formed between the peripheral surface of the reduced extreme lower end of the needle 66 and the tip 86 is an annular chamber 89 which connects at opposite ends with the spray aperture 88 and the annular chamber 85. It will be apparent from the description hereinbefore given that the needle 66 may be raised or lowered to adjust the size of the annular chamber 89 and thereby vary the volume of water emitted from the aperture 88, by rotating the knob 73 secured to the upper end of the needle one way or the other.

Means is provided for limiting the raising of the needle 66 to a predetermined height so that a proper spraying will occur without a waste of water, which comprises the following: Fixed to an upper surface of the casing 57 is a pin 90 which extends into an arcu-

ate elongated depression 91 concentrically formed in the lower surface of the knob 73. The ends of the depression 91 are so disposed that the passage between the annular chambers 85 and 89 will be closed entirely in rotating the knob in one direction until it abuts the pin 90, while the abutting of the pin against the knob in a movement in the opposite direction results in enlarging the passage to its maximum size, thereby limiting the volume of water entering the chamber 89.

The compressed air outlet line 31 leading from the air valve 29 is connected by a suitable coupling 92 at the rear of the pedestal 10 to a pair of compressed air lines 55 branching from the coupling with each line 55 connected to a continuous air channel 95 formed in the horizontal and vertical arms 51 and 56, respectively, of each of the holders 49 supporting the water spraying nozzles 50 or air operated atomizers. Similarly the two water lines 54 from the receptacle 13 are each connected to a continuous water channel 96 formed in the arms 51 and 56 of each of the holders 49. The lower ends of the channels 95 and 96 in the vertical arm 56 each connect with annular chambers 97 and 98, respectively, encircling the arm 56 and formed in the aperture 58 of the casing 57 upon different vertical planes by channels 99 and 100, respectively, disposed at right angles to the channels 95 and 96. Formed in the casing 57 are channels 101 and 102 which connect the chambers 97 and 81 and the chambers 98 and 85, respectively.

The operation of the hereinbefore described grinding apparatus is as follows: Upon closing the switch 20 by operating the key 21 the electrical circuit to the motor 11 is closed, thus the grinding wheels 12 are set in motion. Simultaneously therewith, as hereinbefore described, the normally closed compressed air valve 29 is opened to connect the air supply line 30 with the outlet line 31 and through the coupling 92 each of the air lines 55 and the associated channels and chambers supply compressed air to the nozzles 50, the air entering the aperture 67 of the needle 66 and through the reduced aperture 68 which serves to increase the velocity thereof into the chamber 89. The air in the chamber 89 directly in front of and surrounding the discharge aperture 68 of the needle 66 is caught and carried by the rapidly moving air emerging from the needle 66, thereby creating a partial vacuum in the chamber 85. This vacuum lifts the water from the supply receptacle 13 into the chamber 89.

Upon reaching the chamber 89 the water is broken up into small particles by the high velocity air emerging from the aperture 68 of the needle 66 and ejected through the aperture 88 at the tip of the nozzle in the form of a fine or atomized spray which is directed on the periphery of the grinding wheel 12 in

the position of the nozzle, as shown in the drawings, or may be directed against either side surface thereof as hereinbefore described by rotating the nozzle upon its vertical pivot in case the operator is to grind on the side of the wheel. To regulate the volume of water ejected in the form of spray from the nozzle the operator rotates the knob 73 which raises or lowers the needle 66, the pin 90 and depression 91 cooperating to limit the movement of the needle in either direction. When through grinding, the operator merely operates the key 21 of the switch which opens the circuit to the motor 11 and at the same instant the spring pressed air valve 29 is automatically closed and thereby the spray nozzles become inoperative. As hereinbefore described any waste water along with the condensed spray and grinding particles drops into the pans conveniently arranged, below the wheels, for removal when full, the water supply contained in the receptacle 13 thus being kept free of the used water. When additional fresh water is required it may be readily added to the receptacle 13 by opening the door 14. The lower ends of the water lines 54 are positioned and arranged in the receptacle 13 in such a manner that they are at all times in operative relation with the receptacle even when adding water thereto, as indicated by the dotted line position (Fig. 2).

Although the construction and arrangement of the spray nozzles with their substantially universal adjustment and the control mechanism therefor illustrated in the drawings and hereinbefore described may be used to advantage in connection with the present embodiment of this invention, it should be understood that this invention is not to be limited to the particular construction shown, except as defined by the appended claims.

What is claimed is:

1. In an abrading apparatus, an abrading element, means for applying an atomized spray of liquid thereto, means for adjusting the spray applying means to control the volume of liquid passing therefrom, and means operatively associated therewith for limiting the adjustment of the spray applying means.
2. In an abrading apparatus, a rotary abrading member, an atomizing nozzle directed tangentially of the abrading member for maintaining a continuous atomized spray at the point of abrading and in the region surrounding said point, and means for adjustably rotating the nozzle about an axis inclined to the axis of the nozzle.
3. An abrading apparatus comprising a hollow frame, an abrading element mounted thereon, a liquid holding receptacle in said frame, and means including a tube extending into said receptacle for transferring liquid therefrom to the surface of said abrading element, said receptacle being pivoted near its

lower end and so mounted that its upper end can be swung outwardly while maintaining said tube within the receptacle.

4. In an abrading apparatus, a rotary abrading element, means for applying an atomized spray of liquid thereto, means formed integral with the spray applying means and provided with a plurality of channels communicating with passageways formed in the spray applying means, means for rotatably supporting said integral means in a plurality of adjusted positions, said supporting means having channels formed therein in continuous communication with the channels in the integral means in any of the adjusted positions of the spray applying means, and means for adjustably mounting the supporting means with the spray applying means so that the latter may be moved toward the peripheral face of the abrading element as it becomes worn.

In witness whereof, I hereunto subscribe my name this 15th day of April A. D., 1927.

RUDOLPH ANTHONY SKRIBA.
